GREETING CARD OR THE LIKE

Eugenie J. Jones, Webster Groves, Mo.

Application November 1, 1950, Serial No. 12,809

Term of patent 14 years

(Cl. D59—2)

To all whom it may concern:

Be it known that I, Eugenie J. Jones, a citizen of the United States, residing in Webster Groves, St. Louis County, Missouri, have invented a new, original, and ornamental Design for a Greeting Card or the like, of which the following is a specification, reference being had to the accompanying drawing, forming a part thereof.

The figure in the drawing illustrates a greeting card showing my new design.

The essential features of the design reside in the portions shown in full lines.

I claim:

The ornamental design for a greeting card or the like, substantially as shown and described.

EUGENIE J. JONES.
